GRAMOPHONE TONE ARM MOVING DEVICE

José Soler Martín, Buenos Aires, Argentina

Application February 7, 1947, Serial No. 727,100
In Spain January 22, 1947

2 Claims. (Cl. 274—23)

1

The present invention refers to an improvement in devices for moving gramophone tone-arms.

In present-day gramophones, the device supporting the pickup which, by means of a needle, receives the vibrations engraved in the grooves of the records, consists of an arm turning on a shaft, and the needle, fixed to same, is guided in its displacement by the spiral movement of the grooves. In other words, the needle traverses the arc of a circle centered at said shaft.

In the recording process, the recording device is maintained parallel to itself throughout its travel, and its vibratory plane occupies always the tangent of one of the grooves. During sound-reproduction, however, the needle traverses an arc of a circle in which the different radii corresponding to the several points of contact of the needle, in the grooves, do not correspond to their respective tangents.

During recording, furthermore, the needle, in its advance towards the center of the record, cuts the groove and fixes the recording with greater clearness on the inside edge of same. During reproduction, however, the groove guides the needle, which makes its way to the centre more strongly supported on the outside of said groove.

It is the object of the device according to this invention, to correct these errors, having the vibratory plane of the sound receiver or pickup, at each point of each groove, occupy a position corresponding to its tangent, and causing the needle to be more strongly supported by the inside edge of the same groove.

The first object is attained by means by a sliding motion of the arm on its own turning point, in agreement with the angular displacement of same, an arrangement which makes it possible to modify the effective length of the arm, and which places the needle at a point corresponding to the geometrical tangent of each groove. The second object is attained by placing a suitable spring on the turning shaft so as to have the arm moved towards the center through spring action, the groove serving as a brake to same.

In order that the invention may be more clearly understood, the following diagrammatic drawings, approximate scale 1:2, will now be explained in detail. In the drawings:

Figure I illustrates a plan projection of a tone-arm equipped with a gramophone receiver or pickup, in accordance with the invention.

Figure II is a vertical section of the same, as well as of its moving arrangement, through line A—B of Figure III.

2

Figure III is a diagrammatic representation of the movement of the device with relation to a record.

In Figure I the sound-receiving or pickup device is shown as an arm 3 supporting the receiver or pickup 4 carrying needle 5.

In the figure, the structure is assumed to be transparent in order to show the mounting arrangements.

10 Arm 3 is mounted on horizontal shaft 6, on which it is freely rockable.

This rocker arm shaft 6 is in turn fixed to a plate or elongated piece 7, of suitable cross-section and conveniently bent, one end of which is provided with a socket 8 for a vertical rotating shaft, the other end being equipped with a guide or slot 9 extending in a lengthwise direction.

This lengthwise slot 9 is engaged by a pivot 10, fixed to the supporting base of the entire device, 20 said pivot serving as fulcrum point and at the same time permitting lengthwise sliding motion.

A crank-shaped part 11 includes arms or shafts 12 and 13, vertically placed and parallel to one another at a proper distance, arranged in opposite directions.

25 Shaft 13 is housed within fixed bushing 14, within which it may freely turn, said bushing serving as support and turning center to part 11.

In turn, shaft 12 is housed in bushing 8, serving to support piece 7 and arm 3.

30 A spiral spring 15, acting on shaft 13, urges the arm in the direction indicated by the arrow, that is to say, towards the center of the record.

Figure II shows a vertical section of the device 35 (when same is in position A—B of Figure III) the essential parts of the invention having been shown in broken lines.

Piece 7, with its shaft 6 serving as a rocking support to arm 3, its bushing 8 serving as independent supporting base and swivel 9 serving as a guide to its sliding motion.

40 This swivel is engaged on fixed pivot 10, which serves as a turning spindle for the angular movement of the arm.

45 Crank-shaped piece 11 with shaft 12 serving as rotating support to piece 7, and shaft 13 serving as its own support and turning center.

And fixed bushing 14 housing shaft 13 and serving as supporting base for the whole assembly, spring 15 acts on shaft 13.

The diagram of Figure III shows a gramophone recording 1 centered on shaft 2. Concentric circles, suitably spaced, represent the recording groove spiral.

55 Numerals 10—5 indicate a repetition of Figure

I, the arm being at rest with regard to the record. 10-5', 10-5" and 10-5"" indicate the figure axes of the same arm in its several positions over the record.

The repetition, in broken lines, of the receiving device or pickup over line A-B shows the position same occupies when the needle reaches the more or less central groove of the recorded zone. Its axis A-B forms with the center line 10-2 an angle a (in this case approximately 20°) which is the angle arbitrarily chosen to serve as a basis for the calculations of the drawing in order to establish the position of the third turning center 13. This angle is the one corresponding to the angle of the vibratory shaft of receiver or pickup 4 with the axis of arm 3.

This 20° angle having been taken for a , its complementary angle b is fixed at 70°.

It follows that the geometrical place of the vertices of all the 70°-angles whose sides may pass through points 10 and 2, corresponds to the arc of circle 10-5"2, the center of which is at 16.

Once the correct situation of three points such as 5' 5" 5"" (for example) has been established, the position corresponding to 12', 12", 12"" is obtained by transferring fixed distance 5-12 over their respective radii centered at 10.

And once the positions 12', 12" and 12"" have been fixed, the position of shaft 13 corresponding to the center of the circle passing through those three points, is also fixed.

Operation

The operation of the device is simple, being automatically brought about through the displacement of the needle through the groove, as is usual.

In fact, spring 15 tends to cause the rotation of the arm towards the center of the disc or record, but the receiving needle engaged in the groove acts as a brake on same, permitting only the angular movement of the arm as the spiral groove progresses. In this manner, although the needle may be more strongly supported on the inside edge of the groove, the automatic movement of the arm takes place as controlled by the spiral of the groove.

Arm 3 is pivoted on shaft 6 (for vertical movement) but in a horizontal sense its lengthwise axis always coincides with that of swivel 9.

Crank-shaped part 11, although serving to support the entire assembly, does so floatingly, without hindering its free angular movement.

The angular position of the arm axis is thus determined only by points 10 and 5: and as 10 is a fixed point, the angular movement of the arm is exclusively subordinated to the position of 5, i. e., that of the needle-point.

The needle on being placed in the first groove same will occupy position 5' and the arm will be placed at 5'-10.

As the record turns, the needle will be laterally displaced, first coming nearer to, and then going farther from axis A-B, i. e., angle 5'-10-5" will at first diminish and then increase up to 5"-10-5"".

In agreement with these changes of the angle with regard to vertex 10, the variation of the angle with vertex 13 will also be brought about, obliging shaft 12 in its successive displacements to travel through arc 12'-12"-12"".

The arm will consequently be slidingly displaced in one or the other direction (its values being a function of the variations of the cosine

of the angle at 13) obliging the needle to keep itself practically over arc 5'-5"-5"".

In view of the fact that from any point of this arc 5'-5"-5"" the inscribed angle, its sides passing through points 10 and 2, is always 70°, and as angle a is also constant 17 fixed at 20°, the value of the angle formed by the vibratory shaft with the radius of the record, corresponding to the point of contact, is constantly 90°.

In other words, the vibratory axis of the receiver or pickup occupies with regard to all of the grooves the position of a geometrical tangent, thus being a true repetition of the recording operation.

15 The position of shaft 13 is not critical; it is a function of the position of point 10 and its distance from 2 and the angle may be changed to suit. Those employed have been chosen arbitrarily.

20 Consequently the structure, shape and coupling arrangement of the essential parts of the invention are the sliding support and the crank support, as well as the actuating spring. These parts may be changed indefinitely, mechanically, structurally and artistically without thereby modifying the essential nature of the invention.

25 A structural modification would be, for example, to revert the position of pivot 10 and fix it to the sliding part 7. The guide slot would then be fixed outwardly.

30 The operation as resulting therefrom would be the same, for instead of the mobile slot sliding over the fixed pivot, a mobile pivot would slide over a fixed slot. In that case, a curved slot would have to be calculated for each solution.

35 In the same manner, the shape of the guide-slot may be changed in order to free the arm of adjustment, which is rigorously precise according to the position of the needle, when same is no longer resting in the record groove.

40 It is considered unnecessary to enter into details regarding such changes of shape, owing to the fact that same do not alter the essential nature of the invention as defined in the following claims.

45 I claim:

1. In a gramophone, the combination, comprising a support, a turntable rotatable on the support, a bushing on the support, a crank member 50 including a horizontal portion and upwardly and downwardly extending arms, said downwardly extending arm being rotatable in said bushing, a second member of longitudinally stepped cross-section having means at one end for receiving the upwardly directed arm of said crank member and provided at its opposite end with guide means adapted to engage a pivot pin on said support, a pick-up arm adapted to carry a needle for record engagement, a horizontally disposed transverse shaft for pivoting said pick-up arm to the upper portion of said second member to permit the tone arm to respond to vibrations in a vertical plane, and a coil spring having one end anchored to the support and its other end anchored to the downwardly extending arm of said crank member and tending to rotate said crank toward the axis of the turntable.

2. In a gramophone, the combination, comprising a support, a turntable rotatable on the support, a crank member including upwardly and downwardly extending arms and having said latter arm pivotally mounted in the support, spring means for biasing the crank member to urge its upwardly extending arm toward the axis of the turntable, a second member having a socket at

5

one end for pivotally receiving the said upwardly extending arm, cooperating guide means respectively on the end of said second member opposite the socket and said support, and a pick-up arm connected to said second member by a horizontal pivot. 5
